UNITED STATES PATENT OFFICE.

STEPHEN J. MEEKER, OF NEWARK, NEW JERSEY.

DESIGN FOR A KNUCKLE FOR CAR-COUPINGS.

SPECIFICATION forming part of Design No. 33,591, dated November 20, 1900.

Application filed November 6, 1899. Serial No. 736,051. Term of patent 14 years.

To all whom it may concern:

Be it known that I, STEPHEN J. MEEKER, a citizen of the United States, residing at Newark, Essex county, State of New Jersey, have 5 invented and produced a new and original Design for Knuckles for Car-Couplings, of which the following is a specification, reference being had to the accompanying drawings, forming part thereof.

10 In the accompanying drawings, Figure 1 is plan view of a knuckle embodying my new design, and Fig. 2 is an end view of the same.

The invention consists in the general shape or configuration of the knuckle as shown in 15 said drawings, in which the outer edge line of the same when viewed in plan extends in a substantially straight line 1 on the face side of knuckle, then rearwardly, as at 2, at a somewhat obtuse angle to the face line 1, then inwardly in a curved line 3 on the rear side of the arm 4, and then outwardly in a return-curve 5 toward the end of a rearwardly-projecting extension 6 of the arm 4. From the 20 end of this extension 6 the edge line of the

knuckle extends forward in the line 7 to the 25 inner or rear end of the face side of the arm 4, which face side is formed with two oppositely-tapering surfaces 8 and 9, which extend forward or outwardly from the opposite ends of the arm and merge at a point 10 at 30 one side of the center between said ends, the slope of the surface 8 nearest the face of the knuckle being somewhat shorter and more abrupt than the slope of the surface 9. The upper surface of the arm 4 is inclined downwardly from a point adjacent to the hub 11 to the rear end of its extension 6, as shown in Fig. 2.

Having thus described my invention, what I claim as new, and desire to secure by Letters 40 Patent, is—

The design for a car-coupling knuckle, substantially as herein shown and described.

STEPHEN J. MEEKER.
